UNITED STATES PATENT OFFICE.

SAMUEL L. NEELY, OF LONGTON, KANSAS.

SIGNAL-OPERATING AND COLLISION-PREVENTING APPARATUS.

1,306,833.

Specification of Letters Patent. Patented June 17, 1919.

Application filed June 9, 1915. Serial No. 33,077.

To all whom it may concern:

Be it known that I, SAMUEL L. NEELY, a citizen of the United States, residing at Longton, in the county of Elk and State of 5 Kansas, have invented certain new and useful Improvements in Signal-Operating and Collision-Preventing Apparatus; and I do hereby declare the following to be a full, clear, and exact description of the invention, 10 such as will enable others skilled in the art to which it appertains to make and use the same.

The invention relates to a signal operating and collision preventing apparatus.

15 The object of the present invention is to improve the construction of apparatus for operating signals and preventing head on collisions of trains and to provide a simple, practical and comparatively inexpensive apparatus designed principally for use in connection with an automatic electric block system for trains of a co-pending application and equipped with means for maintaining a proper contact between devices carried by a 20 locomotive and a conductor rail so that the vertical and lateral vibration of a train will not interfere with the operation of the apparatus.

25 A further object of the invention is to provide an apparatus of this character adapted to bring into operation the automatic mechanism of a locomotive when trains approach within the distance of one-half a block of each other and capable of automatically cutting off the steam to the cylinders of a locomotive and of reducing the pressure in the train pipe and of automatically applying the 30 brakes.

Another object of the invention is to provide a signal operating and collision preventing apparatus adapted to be readily arranged to enable locomotives to travel either backward or forward and maintain the proper relation between the circuits, the batteries and the instrumentalities to be operated.

With these and other objects in view the invention consists in the construction and novel combination and arrangement of parts 50 hereinafter fully described, illustrated in the accompanying drawings and pointed out in the claims hereto appended, it being understood that various changes in the form, proportion and minor details of construction 55 may be resorted to without departing from

the spirit or sacrificing any of the advantages of the invention.

In the drawings

Figure 1 is a diagrammatic view illustrating the arrangement of the electric circuits, 60

Fig. 2 is a plan view of a portion of a locomotive illustrating the construction of a laterally slidable support which carries the contact wheels,

Fig. 3 is a side elevation of the same, 65

Fig. 4 is a transverse sectional view of the mechanism illustrated in Fig. 2,

Fig. 5 is an enlarged detail sectional view of one end of the slidable support and the mechanism carried thereby, illustrating the 70 arrangement of the same with relation to the conductor rail,

Fig. 6 is a detail perspective view of one end of the laterally slidable support,

Fig. 7 is a detail perspective view of one 75 of the supporting guide bars,

Fig. 8 is a detail view showing the valve operating means of the locomotive,

Figs. 9 and 10 are detail views of the 80 grade crossing signal,

Figs. 11 and 12 are detail views of the auxiliary switch mechanism of the grade crossing signal.

Like numerals of reference designate corresponding parts in all the figures of the 85 drawings.

In the accompanying drawings in which is illustrated the preferred embodiment of the invention, 1-1 designates angle conductor rails constructed of suitable metal 90 and located at the inner side of the track rails 2 as clearly illustrated in Figs. 4 and 5 of the drawings, but the conductor rails may of course be mounted at the outer sides of the track rails as will be readily understood. Each conductor rail 1 which has vertical and horizontal wings or flanges is secured by bolts 3 or other suitable fastening devices to insulating bars 4 constructed of wood or other suitable material and shaped 100 to fit the groove between the head and the bottom flange of the track rail 2. The wooden bars support the conductor rails and insulate the same from the track rails. The heads of the bolts 3 are countersunk in the 105 supporting bars 4 to prevent them from coming into contact with the web of the track rail. The horizontal flange or wing of the angle conductor rail extends horizontally from the supporting and insulating 110

bar 4 and is located below the plane of the head of the track rail 2 and is adapted to receive a contact wheel 5 carried by a locomotive or other part of a train and adapted 5 to establish electrical connections between devices of the train and the conductor rail 1. The supporting and insulating bars are secured to the rails 2 by means of clamps 6 arranged at intervals and composed of two 10 separable sections or members 7 and 8 which are connected by a transverse bolt 9. The section or member 7 of the clamp is approximately L-shaped and consists of a substantially vertical side provided at its upper 15 end with an inclined rail engaging arm 10 and a horizontal bottom portion 11 extending across the space below the bottom of the track rail 2 and having a reduced terminal portion 12 extending through a perforation 20 or opening of the other side or member 8 of the clamp and secured to the same by a suitable fastening device 13 such as a pin or key but such fastening device may of course be omitted as the sides or members 25 of the clamp are firmly connected and maintained in engagement by the bolt 9 which passes through the sides or members a short distance below the bottom of the track rail 2 as clearly shown in Fig. 5 of the drawings. 30 The side or member 8 consists of a vertical bar or piece extending above the adjacent bottom flange of the rail and secured to a block or filler 14 by bolts 15 or other suitable fastening devices which are also countersunk in the supporting and insulating bar and spaced from the web of the rail but this is not necessary as the filler block or 35 piece is preferably constructed of wood and the clamp is arranged out of contact with the conductor rail 1. The conductor rails and the supporting and insulating bars are preferably of the same length as the track rails and the adjacent ends of the conductor rails are electrically connected by any suitable means and the terminal portions of the conductor rails at switches, crossings and other places where there is a break in the conductor rails are designed to be beveled 40 or inclined to enable the contact wheels to readily ride on to the same without jar or injury. The clamps for securing the supporting and insulating bars to the rails are located between the cross ties and may be 45 of any desired number and they enable the conductor rails to be readily applied to a track.

The conductor wheel 5 is mounted in a fork or frame 16 provided with depending 50 sides 17 extending downwardly from a transverse bar or member 18 and supporting the axle 19 of the contact wheel and also a pair of insulating plates 20 constructed of suitable material and secured to the inner faces 55 of the depending sides or arms 17 and ex-

tending downwardly at opposite sides of the lower portion of the contact wheel 5 and adapted to prevent the same from accidentally coming in contact with the rails 2 of the track. The insulating plates 20 terminate short of the conductor rail and as the construction disclosed in the present application, obviates the necessity of insulating the track rail, the apparatus may be installed at a relatively low cost. The fork 75 or frame 16 is provided with upwardly extending sides or arms 21 slidable in guides 22 of a central tube 23 which receives a stem 24 of the fork or frame 16. The guides 22 consist of small tubes and the stem 24 receives 80 a coiled cushioning spring 25 interposed between a suitable stop or projection 26 of the stem 24 and an upper stop 27 which may consist of a cap of the tube 23. This will enable the coiled spring to cushion the contact 85 wheel and will permit the latter to have relative vertical movement so that the vertical vibratory movement of the train will not interfere with the proper electrical contact between the said wheel and the conductor 90 rail.

The tube 23 is suitably secured to and insulated from a horizontal support 29 constructed of any suitable material and extending across a locomotive or other portion of 95 a train from one side to the other thereof and provided at its ends with projections 30 which are slidably mounted in openings 31 of side bars 32 designed to be bolted or otherwise secured to the journal boxes 33 of 100 a locomotive truck, but the support 29 may be mounted in any other desired manner. The projections 30 are slidably mounted in the said openings 31 so that the support 29 is capable of movement laterally of a train 105 with respect thereto so the lateral vibrations of a train will not carry the contact wheels beyond the conductor rails and interfere with the electrical connections between the same and the said wheels. In order to maintain the laterally movable support in proper relation with the conductor rail it is provided with depending vertically disposed rollers 34 provided at their upper ends with 110 journals 35 suitably mounted in the support 115 29 and adapted to rotate to enable them to move frictionlessly along the track rails. The vertical rollers are adapted to engage the track rails at the inner sides thereof to limit the lateral movement of the support 120 29 so that the lateral vibrations of the train will not carry the support far enough in either direction to move the wheels 5 out of contact with the conductor rails.

The vertical rollers which are adapted to 125 operate as a guard to protect the contact wheels and to clear a path in snow or through other obstructions are designed to be located in advance of the contact wheels. The sup- 130

port is designed to be provided at each end with three contact wheels 5 and 5^a, the center wheel 5 being connected with the devices of the locomotive while the end wheels 5 at the opposite sides of the support are designed to be connected by wires 36 and 37 with switches 38 and 39 for short circuiting the devices of the locomotive. When the locomotive is short circuited by the switches 38 and 39, the conductor rails 1 are connected electrically and the current may be made to pass from the conductor rail of one side of the track to the conductor rail of the opposite side.

15 The mechanism carried by the locomotive comprises in its construction a motor 40 provided on its shaft with a drum 41 adapted to have wound thereon a flexible connection 42 which may be in the form of a belt or cable or similar device adapted to pass over a pulley 42 of a suitable valve 43 of a steam or air pipe 44. The flexible connection is provided at its free end with a weight 45 slidible in a suitable guide 46 to prevent the vibration of the train from swinging the weight and the flexible connection. The weight is adapted to move the flexible connection in one direction when the circuit in which the motor is arranged is deenergized 25 for returning the valve to its normal position and when the circuit including the said motor 40 is energized, the motor will rotate the drum 41 and wind the flexible connection thereon and thereby rotate the pulley 42 and open or close the valve as required. After an operation of the valve by the motor, the latter may be stopped or stalled but held against retrograde movement by the current so that the valve will be maintained 30 in such operated position. The motor may, for instance, be such that its power will be sufficient to operate the valve but not strong enough to injure the mechanism which will hold the motor against movement by the current.

40 The flexible connection 42 is designed to be of a length to move the valve to its motor operated position so that the valve will remain in such position while the current is on, but it is obvious that various 45 means of either cutting off the current or interrupting the actuation of the motor irrespective of its size may also be employed, such for instance, the opening of the switches 55, 58, 63 which control the feeding of the current to said motor 40, and which will be more fully described hereinafter. One or more motors may be employed and the valve if a steam valve is moved to a closed position to prevent steam from being fed to the 50 cylinders of the locomotive and if an air brake valve will be moved to an open position to permit an escape of the air pressure of the train pipe to reduce the pressure sufficiently to effect an emergency or other 55 application of the brakes of the train. Only

one pipe and valve are illustrated in the accompanying drawings as merely a duplication thereof is required to operate the valves of both the steam and air pipes. Also instead of employing a flexible connection and a pulley any other suitable means may be used for connecting the valve with the motor and for shutting off the motor actuating current after the operating of the devices controlling the brake and the power. This may also be accomplished by operating the switches 55, 58, 63 arranged between the motor and the source of electric energy, and about to be described.

One of the terminals of the motor is connected by a wire 47 with the axle 48, a brush 49, and an annular contact 50 being employed. The annular contact may consist of a split ring clamped around the axle or any other desired construction may of course be employed.

The other terminal of the motor is connected by a wire 51 with a battery 52. The wire 51 is provided with branches 53 and 54 connected with the two poles of the battery 52, a switch 55 being connected with the branches 53 and 54 so as to electrically connect the wire 51 with either of the poles of the battery 52. This construction enables the motor circuit of the locomotive to be reversed to arrange it to suit an engine traveling either backward or forward inasmuch as the poles of the batteries on both trains being always arranged on the same side in the forward direction of the train the polarity will be different for forwardly running trains in the case of head-on collisions on the one hand and rear-end collisions on the other hand, while, when the locomotive positioned on the particular section of track reverses its direction of movement the polarity is, of course, not affected while the relative position with relation to the direction of movement is changed. The poles of the battery 52 are also connected by wires 56 with the contact wheels 5 and with the conductor rails 1 by means of the said contact wheels. Switches 58 being connected with the wires 56 so that either pole of the battery may be connected with one of the conductor rails while the other pole of the battery is connected with the motor. The circuit is completed as hereinafter fully explained when a connection is made between the conductor rail and the track rail.

The battery 52 is arranged in rear of a front battery 60 having its poles connected by wires 61 and 62 with the angle rails, a switch 63 being connected with the wires 61 and 62 so that either angle rail may be connected with either of the poles of the battery 60. The wires 61 and 62 as clearly illustrated in Fig. 2 of the drawings are connected with the wires 56 and thereby connected with the contact wheels but separate

connections with the contact wheels and the conductor rails may of course be employed if desired. In Fig. 2 of the drawing, the wires 56, 61 and 62 are shown connected with a single wire leading to the tube 23 of the central contact wheel 5, but in the diagrammatic view, Fig. 1, the wires 56, 61 and 62 are shown, for convenience of illustration, extending directly to the conductor rails 1 with which the said contact wheels engage.

The diagram shown in Fig. 1 of the drawings illustrates the arrangement of the circuits of two locomotives approaching each other. The track rails are alternately arranged with respect to the insulation 64 which separates the adjacent track sections. The insulation occurs at the ends of the blocks and also at a point midway between the same and as it is necessary for two locomotives to reach the same continuous track section in order to operate the devices for automatically applying the brakes and stopping the train it will be clear that the locomotives have one-half the length of a block in which to operate their devices before coming in contact with each other. This will be ample to prevent head on collisions and it will be clear that if the track sections were insulated only at the ends of a block that a collision might occur at such point whereas with the alternate insulation of the rails this is effectively prevented. Each conductor rail may be connected by a wire 65 with a motor 66 of a signal termed for convenience, a grade crossing signal, Fig. 1 illustrating diagrammatically the relative arrangement of the train stopping devices in combination with such signaling devices in the case of continuous as well as in the case of interrupted conductor rails 1, and the motor is connected by a wire 67 with an auxiliary switch mechanism 68 of the grade crossing signal at the opposite side of the track. The auxiliary switch mechanism of this grade crossing signal is connected by a wire 69 with a switch 70 which is connected by a wire 71 with the other conductor rail. The grade crossing signals which form the subject matter of a co-pending application are reversely arranged for operation by locomotives traveling in opposite directions. The motor of the signal circuit may, for instance, be a small motor, similar to a toy motor, as explained in the aforesaid application, so that only a relatively low current of exceedingly small voltage will be found necessary to secure an operation of the motor. The said signal circuit and the signaling devices may be entirely left out or they may be used for the purpose of operating train blocking or controlling means in connection with trains approaching on the grade crossing tracks. As here shown the signaling

and similar devices are operated from the front battery 60 of a train approaching the grade crossing, while the signaling device on the opposite side of the track is operated from the train approaching from the other end of the track. Well known devices may of course, be resorted to in order to increase the working voltage of the battery 60 whenever necessary. The motor 66 of each grade crossing signal is connected by a train of gears 72 with a pinion 73 which meshes with a vertically movable rack bar 74 and the latter carries a switch arm 75 which is movable upwardly and downwardly between upper and lower contacts 76 and 77. When one of the signal motor circuits is energized, it carries the switch arm upwardly and opens the switches of the motor circuit of the grade crossing signal at the opposite side and maintains the said circuit open so that an operation of the motor of such grade crossing signal will be impossible. The auxiliary switch mechanism of each grade crossing signal includes a motor 78 which is connected by a train of gears 79 with a pinion 80 which meshes with a vertically movable rack bar 81. The rack bar 81 carries a switch arm 82 which is movable between upper and lower contacts 83 and 84.

Referring particularly to Fig. 1 of the drawings and considering the track as running east and west, the front battery 60 reaches the north and south angle rails through the switches 63 and the contact wheels. This battery has its zinc to the south and the copper to the north and when it is desired to run the locomotive backward the switches are thrown which will place the battery in harmony with an engine in rear so as to prevent a collision while running backward. Also when a train is out as a work train the switches may be used to avoid operating the signal mechanism so that a grade crossing signal will not be held too long against the public. When this is done a flagman may be sent out. The current from the battery 60 flows through the south conductor rail through the motor in the south grade crossing signal and across the track through the switches in the other grade crossing signals and the auxiliary switch mechanism thereof back to the north conductor rail and up through the contact wheel to the copper of the battery. Although zinc and copper are referred to as the poles of the battery any other suitable form of battery may of course be employed and instead of using a battery a dynamo or any other source of current supply may be utilized as for instance on electric roads the power of the road may be employed for operating the signals and the motor of the locomotive. On both trains the identical poles of the rear batteries 52 are connected to the motor 40 and are open to the con-

ductor rails 1, while the opposite poles of the batteries are connected to the said conductor rails so that only one connection between the battery 52 and the conductor rails 5 is necessary for closing the train motor circuits as the return of the current is made through the track rails. The zinc of the battery 52 is connected with the contact wheel at the south conductor rail by the 10 wire 56. Whenever there is a break in the conductor rails 1 on switches and crossings, as stated above, the conductor rails are bridged by bridge wires 86, 87. The south conductor rail may be connected by the 15 bridge wire 86 with one of the wires 87 which are connected with the upper contact of the grade crossing signal so that when one of the grade crossing signals is operated the wires 87 will be connected at the 20 opposite side of the track, and the other wire 87 is connected by a bridge wire 88 with the south conductor rail of the next block. This connects the south conductor rail of block number one with the south conductor rail of block 2 and the current is 25 permitted to flow through the south contact wheel of engine number two to the copper pole of the rear battery. In the construction shown in the drawings by way of example the bridge wires 86, 87, 88 are situated 30 on one side of the track only, and are connected by means of the switch arms 75 when not operating the side crossing devices; the bridging of the conductor rails 35 of the other side of the track is effected in this case by the short circuits 36, 37, 38, 39 situated upon the supporting plate 29. The current flows from the copper pole to the zinc pole and through the motor of engine number two to the axle and thence to 40 the rail traveling along the north rail and passing up through the wheel and axle of engine number one to the motor thereof. When the trains approach between the 45 blocks there is no need of the bridge wires as the angle rails are continuous. It will be seen that both of the motors of the engines are in circuit with each other and with the batteries or other source of current supply so that the valve for controlling 50 the air brake and the steam will be operated should the locomotives be permitted to proceed with such circuit closed. The front batteries 60 are always in circuit 55 so that a train having the right of way on a track is in position to operate the motor 66 of the signaling or similar devices situated on both sides of the track, the motor of one side of the track by operating the 60 switch arms 75 and 82 being sufficient in order to release the signaling or equivalent devices on both sides of the track. The path of the current will for instance, be as follows: south side of battery 60, south conductor 1, wire 65, south motor 66, wire 67, 65 contact 68, wire 69, 71, north conductor rail 1, back to north side of battery 60. By operating the switches 63, the front batteries may be cut out, and the signaling circuit rendered inoperative thereby. In the case 70 of trains moving west or east, that is to say from right to left or vice versa along the track 2, the path of the currents is as follows:—In the case of rear-end collisions from battery 52 south, conductor 1 south, 75 battery 61 (or short circuits 36, 37) conductor 1 north, then on second train through short circuits 36, 37 to conductor 1 south, through battery 52, wire 51 to motor 40, axle 48, track rail 2, to motor 48 of first 80 train, and on this train back to north side of battery 52. In the case of head-on collisions which is represented in Fig. 1 of the drawing the path of the current is as follows: From south side of battery 52, south 85 conductor rail 1, battery 60 (or short circuits 36, 37), conductor 1 north to wire 56 second train north side, switches 58, 55 by way of rear battery 52 and wire 54 of second train, wire 51, motor 40, axle 48, track 90 rail 2 back to first train; axle 48, motor 40 of first train, wire 51 back to north side of battery 52 first train. This description of circuits applies to the case where the connections on both trains are exactly the same 95 so that the train controlling devices of two trains entering the same block will be automatically operated; but it is obvious that if the train stopping device of an approaching train is to be operated by the engineers 100 of said trains the several devices may be differently connected. The motors 40 may be cut out after a certain time by automatic means or they may be cut out by the engineer operating the switches. The duration 105 of the operation of the signaling or similar devices arranged on both sides of the track in the case of trains retained on the corresponding block by the train stopping device of this invention, depends upon the construction of the motors 66 and 78 and of their motion-transmitting devices. The construction may of course, be such that such signaling or similar devices are only cut out by hand after having been operated by the 110 safety devices of my invention. 115

In this manner it is immaterial whether an engineer be careless, dead or otherwise incapacitated the motor for controlling the air brake and the steam valve will be automatically operated and will effectively prevent two trains from colliding. 120

What is claimed is:—

1. In an apparatus of the class described including a valve having a pulley, a motor 125 provided with a drum, a flexible connection provided at one end with a weight and extending over the pulley and arranged to be wound around the drum for operating the valve and a motor circuit including a source 130

of current supply, a track rail and a conductor rail.

2. In a device of the class described a movable supporting frame, a motor on said frame, a railroad track, a source of electric energy on said frame, a conductor rail, electric conducting means on said frame and movable along said rail, a transverse axle, electrical connecting means between said motor and one pole of the source of elec-

tric energy, electric connections between the other pole of said source and said motor, and electric connections between said motor and said axle.

In testimony whereof I affix my signature 15
in presence of two witnesses.

SAMUEL L. NEELY.
